CLAIM

The ornamental design for a static mixer, as shown and described.

DESCRIPTION

FIG. 1 is a top perspective view of a static mixer;

FIG. 2 is an end elevation view thereof;

FIG. 3 is a top plan view thereof;

FIG. 4 is a side elevational view thereof;

FIG. 5 is a cross-section view taken from line 5-5 of FIG. 3;

FIG. 6 is an enlarged detail view of portion 6 of FIG. 8;

FIG. 7 is a bottom perspective view thereof;

FIG. 8 is a side elevation view thereof; and,

FIG. 9 is an enlarged detail view of portion 9 of FIG. 1.

The dot dash broken line indicates cutoff boundaries for enlarged detailed portion views and form no part of the claim.
